The ornamental design for a horizontal hexagonal eyeglass lens with aperture, as shown and described.

DESCRIPTION

FIG. 1 is a front environmental view of the horizontal hexagonal eyeglass lens with aperture, depicting a horizontal hexagonal aperture;

FIG. 2 is a front perspective view of the horizontal hexagonal eyeglass lens with aperture, depicting the horizontal hexagonal aperture;

FIG. 3 is a front view thereof;

FIG. 4 is a rear view thereof;

FIG. 5 is a right side view thereof with a left side being a mirror image; and,

FIG. 6 is a top view thereof with a bottom view being a mirror image.

The broken lines are included for illustrative purposes only and form no part of the claimed design.
